CLAIM

The ornamental design for an air vent plate for car window, as shown and described.

DESCRIPTION

FIG. 1 is a perspective view of an air vent plate for car window showing my new design;

FIG. 2 is a front elevational view thereof;

FIG. 3 is a rear devotional view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof;

FIG. 9 is an enlarged view of the portion of FIG. 1 outlined by the dot-dash broken line;

FIG. 10 is an enlarged view of the portion of FIG. 2 outlined by the dot-dash broken line;

FIG. 11 is an enlarged view of the portion of FIG. 3 outlined by the dot-dash broken line; and,

FIG. 12 is an enlarged view of the portion of FIG. 8 outlined by the dot-dash broken line.

The dot-dash broken lines surrounding portions of the air vent plate for car window in FIGS. 1-3 and FIGS. 8-12 form no part of the claimed design.
